(57) **CLAIM**

The ornamental design for a pool table base, as shown and described.

DESCRIPTION

FIG. 1 is a perspective view of a pool table base showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

FIGS. 4—7 disclose single unit of the pool table base. The broken lines of FIG. 1 are for illustrative purpose and form no part of the claimed design.
